UNITED STATES PATENT OFFICE

114,365

DESIGN FOR A TEA MAKER

Simon W. Farber, Brooklyn, N. Y.

Application February 2, 1939, Serial No. 82,715

Term of patent 14 years

To all whom it may concern:

Be it known that I, Simon W. Farber, a citizen of the United States, residing at Brooklyn, in the county of Kings and State of New York, have invented a new, original, and ornamental Design for a Tea Maker, of which the following is a specification, reference being had to the accompanying drawings, forming part thereof.

I claim:

The ornamental design for a tea maker, substantially as shown.

SIMON W. FARBER.
